HYDROSTATIC FUSE

Gaynor O. Rockwell, Houston, Tex., assignor to the United States of America as represented by the Secretary of the Navy

Application February 20, 1946, Serial No. 649,093

3 Claims. (Cl. 102—70.2)

1

The present invention relates to a fuze for use in a fluid medium, such as in an underwater explosive device operated by the pressure of water at a predetermined depth. More particularly, it relates to a detonator which is armed by a hydrostatic or equivalent threshold pressure at one predetermined depth, and into which water or an equivalent fluid medium forces its way at another pressure at a much greater predetermined depth to energize a sea cell, the output of which is supplied to an electric cap or squib to initiate an explosion.

Existing pressure-operated detonators have the disadvantage that they are not operable at great hydrostatic pressures present at depths of 400 to 1,000 feet. Existing detonators have the further disadvantage that they are not capable of being re-designed to operate at hydrostatic pressures of a high order.

It is an object of the present invention to provide a hydrostatic fuze which will be operable at hydrostatic pressures of a high order.

A further object of the invention is to provide a hydrostatic fuze which will be armed by a threshold hydrostatic pressure at a predetermined depth and will be subsequently detonated at a greater predetermined depth.

Another object of the invention is to provide a hydrostatic fuze which is rugged, reliable, positive in action, readily manufactured and which occupies a minimum amount of space.

These and other objects of the invention will be better understood by reference to the following description and accompanying drawing, in which

Fig. 1 is a perspective view showing the detonator as applied to an explosive device;

Fig. 2 is a perspective view of the detonator;

Fig. 3 is a plan view of the lower end of the detonator;

Fig. 4 is a vertical section as indicated by the line 4—4 of Fig. 3;

Fig. 5 is an exploded sectional view of the rupturing diaphragm assembly;

Fig. 6 is a vertical section as indicated by the line 6—6 of Fig. 3;

Fig. 7 is a perspective view of the shutter and the shutter release plate;

Fig. 8 is a vertical section of the shutter as indicated by the line 8—8 on Fig. 7, and

Fig. 9 is a vertical section of the shutter as indicated by the line 9—9 of Fig. 7.

Referring to Figs. 1 and 2, a base 20 carries the working parts of the detonator, represented generally at 22, and is attached to a body 24 which contains the main explosive charge.

The working parts include current generating means using a salt water electrolyte and known as a delayed action sea water battery, two rupturing diaphragms, a safety shutter, a shutter re-

lease, a shutter-release operating means, a cap, a tetryl train, a booster charge, and the necessary containing and connecting parts.

Referring to Figs. 3, 4, and 5, an initially dormant sea water battery 26 is contained in a chamber 28 in the base 20 where it is sequestered from the external fluid medium. The sea water battery 26 comprises a series of electrode plates 26a which are secured in place by means of a central rod 26b and separated therefrom by means of a dielectric washer 26c. It will be understood that other forms of sea water batteries may be utilized as current generating means, such as the types disclosed in copending applications, Ser. No. 476,062 filed by Lewis E. Kissinger et al., now Patent No. 2,526,670, or Ser. No. 711,302 filed by F. F. Farnsworth, et al. The chamber is closed by a threaded plug 30 which bears on a washer 32 and is furnished with spanner sockets 34. Two fluid passages 36 leading from the chamber to the sides of the base are closed by the rupturing diaphragm assemblies shown in detail in Fig. 5.

The diaphragm assembly consists of a resilient washer 38, a thick metal disk 40 having a central hole 42 with sharp edges, a thin metal disk 44, which aids in the sequestration of the battery, another resilient washer 46, and a threaded plug 48. The threaded plug has spanner sockets 50. A hole 52 parallel to the flat surfaces of the plug intersects the spanner sockets and an axial hole 54 in the underside of the plug.

One terminal of the sea cell is connected through a hermetically sealed terminal 56 to a contact 58 carried on the upper surface of the base by an insulating strip 60, the other terminal (not shown) is grounded to the metal of the base.

Referring now to Fig. 6, the base 20 also supports the shutter-release operating mechanism. This consists of a tubular metal bellows 62, fastened at its outer end to the outer end of a tube 64 which passes through the base. The inner end of the bellows is secured to a plunger 66 which is slidable in the tube. This plunger is the operator of the detent presently described. An extension rod 68 on the plunger extends down through the bellows and far enough beyond the surface of the base to permit insertion of a safety wire 70.

A plate 72 is secured to the upper end of the plunger 66 to form the shutter release. Two plungers 74 fastened to the shutter release plate project down into holes 76 in the base through threaded plugs 78. Springs 80, bearing against the undersides of the plugs and against shoulders 82 on the plungers, resist upward movement of the shutter-release mechanism.

Referring again to Fig. 4, the base 20 is surrounded by a shutter housing 84 and a booster carrier plate 86. These, together with the base,

form a space in which a slide member or shutter 88 is laterally slidable. The booster carrier plate has a threaded hole on its upper surface into which a booster charge contained in a cup 90 can be screwed.

Referring now to Figs. 7, 8, and 9, the shutter 88 is rectangular in shape with a longitudinal groove 92 in its front face. An opening 94 in the lower side of the groove engages a projection or detent 96 on the edge of the shutter release plate 72 which operates as a detent to hold the shutter in the "safe" position.

Spring-operated plungers 98 in one end of the shutter move it laterally when it is released, and a similar plunger 100 in the back face enters a hole 102 in the shutter housing 34 (Fig. 4) to lock it in the "armed" position.

The shutter has a cavity 104 in the lower surface closed by an insulating cover plate 106. Mounted in holes opening upward from this cavity are a cap or squib 108, a contact pin 110 and two terminal screws 112, only one of which is shown. The cap 108 is so located that, when the shutter is in the "armed" position, it is aligned with a tetryl train in a hole 114 in the booster carrier plate 86 as shown in Fig. 4. The contact pin 110 projects through a hole in the cover plate 106. It is mounted, with its driving spring 116, in a tubular holder 118 which, in turn, is held in an insulating cup 120. The terminal screws 112 are provided to eliminate the necessity of soldering the leads to the cap 108 with the attendant hazard of a possible explosion from the heat. One of these screws is mounted in the shutter in an insulating bushing 122 and provides a means for joining one of the cap leads to the lead from the contact pin. The other screw is used to ground the other cap lead.

The shutter is prevented from moving under the influence of the spring of the locking pin 100 by the shutter release plate 72 and a stop bar 124 attached to the booster carrier plate 86.

In operation, water enters the bellows 62 (Fig. 6) around the rod 68 and, as the device sinks and the pressure increases, tends to expand the bellows and force the shutter release plate 72 upward. The springs 80 are gradually compressed under the effect of the increasing pressure and finally permit the plate to rise high enough for the projection 96 (Fig. 7) to clear the opening 94 in the shutter. The plungers 98 can then force the shutter to move laterally, aligning the cap 108 with the tetryl train in hole 114 and bringing the contact pin 110 onto the contact 58, thereby arming the detonator. This happens at a depth dependent on the strength of the springs 80.

At the same time water enters the portion of the rupturing diaphragm assemblies external to the thin disks 44 by way of the spanner sockets 50 and the communicating passages 52 and 54 (Figs. 4 and 6). Pressure is exerted on the thin disks 44 tending to shear them on the sharp edges of the holes 42 in the disks 40. At some depth greater than that at which the arming action takes place, the pressure against the disks is great enough to shear one of them, admitting water to the sea-cell cavity 28. When the plates of the sea cell 26 are contacted by sea water, they produce a voltage which causes a current to flow through the cap 108 by way of the hermetically sealed terminal 56, the contact 58, the contact pin 110 and the wiring in the shutter, with the return circuit formed of the metal of the device. The cap explodes, setting off in turn

the tetryl train 114, the booster 90 which detonates the main charge 24.

I claim:

1. In a hydrostatic fuze including an electrically detonatable squib and a delayed action sea water battery having an entry port normally closed by a diaphragm capable of being fractured at a predetermined pressure for permitting the entry of sea water for activating the battery, means for connecting said battery to said squib comprising a slideable connecting member having an armed and an unarmed position, resilient means urging said member toward said armed position, detent means normally retaining said connecting member in the unarmed position, and fluid pressure operated means including a bellows expansible by a predetermined fluid pressure of a different force than said first-mentioned pressure for moving said detent to release said connecting member for movement to its armed position.

2. A hydrostatic fuze including an electrically detonatable squib and a delayed action sea water battery having an entry port normally closed by a diaphragm capable of being fractured at a predetermined pressure for permitting the entry of sea water for activating the battery, in combination, a slideable connecting member having an armed and an unarmed position, said member having a groove and a communicating opening, resilient means urging said member toward said armed position, detent means operable beside said member and having a projection occupying the opening to detain said member in the unarmed position, and spring-loaded fluid-pressure operated means coupled to said detent means, being operable by a fluid pressure different from the predetermined pressure aforesaid, for moving said detent means counter to its spring loading and in respect to said connecting member to displace the projection into the groove.

3. A hydrostatic fuze having a base including a chamber with a passage potentially open to water access and a bellows open to water entry, a dormant battery situated in the chamber and a rupturable diaphragm fixed across the passage to exclude the water until a rupturing pressure is imposed thereon, a spring-loaded member carrying a squib detonatable by activation of the battery, said squib and battery being situated in a normally open circuit, interengaging components forming detent means initially holding said member in an unarmed and circuit-opening position, and a plunger and plate assembly, the plate of which has one of the detent components, the plunger of said assembly being operative by expansion of the bellows to displace the detent means for release of said member to the armed and circuit-closing position.
